UNITED STATES PATENT OFFICE

JOHN RINNE, OF UPPER DARBY, PENNSYLVANIA, ASSIGNOR TO THE BABCOCK & WILCOX COMPANY, OF BAYONNE, NEW JERSEY, A CORPORATION OF NEW JERSEY

BOILER

Application filed January 5, 1931. Serial No. 506,568.

This invention relates to water tube boilers, and more particularly to water tube boilers characterized by multiple gas passes in which one of the passes is through gas tubes disposed interiorly of the water tubes.

One of the objects of my invention is the provision in a steam boiler of the character described of a special baffle arrangement providing an effective flow of heating gases across the combination tubes and a heating gas outlet at a location insuring a desirable distribution of the heating gases to the gas tubes, while affording a compact boiler structure.

Other objects will be apparent to those skilled in this particular art from the description in the specification in connection with the appended drawings, in which—

Fig. 1 is a side elevation, partly in section, of a boiler illustrating the invention;

Fig. 2 is an enlarged side elevation, partly in section, of a structural detail of the invention;

Fig. 3 is an end view, in section, of a boiler taken along the line 3—3 of Fig. 1.

In the embodiment of the invention chosen for purposes of illustration, a drum 1 is connected by means of nipples 2 to downtake headers 3. One end of tubes 4 is connected to the downtake headers 3 and the other end thereof is connected to uptake headers 5. The tubes 4 are compound and include an outer tube 40 and an inner tube 35. These tubes are so arranged with respect to each other and the headers 3 and 5 that the tube 35 is open to the hot gases of combustion in the boiler which will sweep therethrough, and the heat absorbing fluid (which may be water) used in the operation of the boiler is contained in the space between the two tubes.

A row of tubes 8 connected to both rows of headers 3 and 5 are plain water tubes. Below the row of tubes 8 is another row of water tubes 9 connected at one end in the headers 5; these tubes extend parallel to the tubes 4 and 8 for a portion of their length and are then curved downward at 10, and the other end is expanded in downtake headers 11 which are connected to the downtake headers 3 by means of nipples 12. Steam and water circulators 6 connect the upper ends of the uptake headers 5 with the drum 1, completing the steam and water circulatory system.

A mud drum 13 is connected with the headers 11 by means of nipples 14. Baffling 17, made of suitable refractory material, is supported by the tubes 4 and 8 in its upper portion, and its lower portion 18 rests upon and is supported by the curved portion 10 of the tubes 9.

A combustion chamber 20 is formed below the steam generating tubes 4, 8 and 9 by the walls of the boiler setting. Front wall 21 of the boiler casing extends upward from the boiler setting and forms a gas chamber 22 at one end of the tubes, the gas chamber being bounded by the wall and the headers 3. Another wall 23 of the boiler casing forms with the headers 5 a second gas chamber 24. The walls 21 and 23 are substantially vertical and make, with their respective inclined headers 3 and 5, gas chambers of substantially trapezoidal cross section so arranged as to insure equalization of the gases through the gas tubes during normal operation of the boiler.

Superheater tubes are disposed in the upper portion of the boiler and are expanded in superheater headers 26, 27, 28 and 29 which are located outside of the path of the gases of combustion and are partially shielded therefrom by the nipples 2.

In the operation of this boiler, the gases of combustion from the combustion chamber 20 sweep across the tubes 9, 8 and 4 in a pass formed by the baffle 17 and the headers 5. These gases then sweep across the superheater tubes and down across the tubes 4 and 8 into an exit chamber 30 which is formed between the tubes 8 and the curved portion 18 of the baffle. From there the gases flow to the gas chamber 22 and then through the gas tube portion 35 of the compound tubes 4 to the gas chamber 24, and thence up the stack 36.

Fig. 2 shows a simple way of connecting the compound tubes with one header. The outer tube 40 is expanded in the header in

the usual manner. The inner tube 35 extends through the tube 40 and through the header and is seated in an auxiliary seat portion 37 which is fitted in the outer wall of the header and secured by a suitable nut 38. This construction provides an annular chamber between the tubes 40 and 35 which receives water from the header. The tube 35 is open to the gas chamber 22 and the gases of combustion delivered to the combustion chamber flow therethrough.

The other end of tube 40 is expanded in the inner face of header 5 in the usual manner, and the tube 35 is expanded in a plate 41 bolted to the outside face of the header 5. This manner of connecting the tubes with the header is such that steam and water may circulate in the annular chamber between the tubes 35 and 40, while the tube 35 is open to the gas chambers 22 and 24 so that the gases of combustion will flow therethrough. While this manner of connecting the tubes is convenient and effective, and is such that they may be readily removed at any time that a replacement is necessary, a specific manner of connecting the compound tubes is not contemplated as a part of this invention.

From the foregoing description it is apparent that this invention provides a multiple pass boiler which is compact and in which the effectiveness of heat transfer is extremely high, as an additional heat absorbing surface exposed to the hot gases of combustion is provided in the same space ordinarily taken up by water tubes alone, and while a specific

embodiment of the invention has been described in some detail, it is understood that substitutions, changes and additions may be made therein within the spirit of the invention as limited by the appended claims.

What I claim is—

1. A water tube boiler including a bank of inclined tubes with gas tubes located therein; a lower row of water tubes located below the bank of inclined tubes and above a combustion chamber, said lower row of tubes being curved downward at one end; a baffle supported by said lower row of tubes and resting on the curved part thereof, constructed to direct gases of combustion from the combustion chamber across said tubes in at least two directions, and thence through the interiorly located gas tubes.

2. In a water tube boiler, a bank of inclined water tubes disposed above a combustion chamber and having uptake and down-take headers connected therewith, a boiler casing associated with said tubes and headers forming a gas space at the ends thereof, gas tubes located inside certain of the water tubes, a lower row of water tubes bent downward at one end, a baffle associated with the tube bank covering the lower row of tubes at the bent portion thereof and being supported thereby; the tubes, baffling and gas spaces being so arranged that gases of combustion will be directed across the tubes at least twice, and thence through the gas tubes.

JOHN RINNE.
